UNITED STATES PATENT OFFICE.

THEODORE L. NEUMANN, OF DAYTON, OHIO, ASSIGNOR TO THE DAYTON PAPER NOVELTY COMPANY, OF DAYTON, OHIO, A CORPORATION OF OHIO.

TERRACE DISPLAY MEANS FOR PAPER BOXES.

Application filed August 29, 1927. Serial No. 218,010.

This invention relates to new and useful improvements in terrace display means for paper boxes.

It is the principal object of my invention 5 to provide for an independent set-up or for the inclusion in a box containing merchandise, a collapsed blank which may be easily folded to a position for insertion in the box above the articles therein to provide a terrace 10 raced support for the display of some of them.

It is also an object of my invention to provide on the blank, an extension above its terraced portion to display legends concerning the articles which the box contains.

15 Other important and incidental objects will be brought out in the following specification and particularly set forth in the subjoined claims.

In the accompanying drawings illustrating 20 my invention, Figure 1 is a plan view of the blank from which my terraced display insert is made. Figure 2 is an exterior view of one side of the blank after being assembled in its terraced form. Figure 3 is a sectional view 25 taken through the assembled blank. Figure 4 is a perspective view of the assembled blank. Figure 5 is a perspective view of the assembled terrace unit within a box, showing in dotted lines a bar of candy resting upon one 30 of its ledge portions. Figure 6 is a plan view of a portion of a blank formed in a different manner to provide the terraced insert. Figure 7 is a sectional view taken through the 35 assembled blank. Figure 8 is an external view of one side of the same. And Figure 9 is a view of said blank side before the terraced top is secured thereto, showing the pointed supporting sections on the flap.

Referring to the accompanying drawings 40 for a detailed description of my invention, the numeral 1 designates a blank which may be made of paper or metal. This blank in Figure 1 comprises a middle section formed a short distance above its bottom with a horizontal crease line 2. Parallel with the latter line, and a short distance above it, is a second crease line 3. A space of a narrow width is defined between the latter line and a third crease line 4 above it.

The portion of the blank between the crease 50 lines 2 and 3 terminates beyond the middle section of the blank in ears 5 and 6 that have reduced slot entering ends 7. This blank portion between the crease lines is adapted to be bent to a horizontal position to form a 55 supporting surface 8 for an article of merchandise such as a bar of candy 9 shown in dotted lines in Figure 5. The part of the blank between the crease lines 3 and 4 is bent to provide a vertical back 10 for the article 60 of merchandise displayed.

In the drawings, the blank 1 is divided into four portions 8 that provide the horizontal supporting surfaces that are adapted to be arranged in terraced relation by folding the 65 blank as shown in Figure 4. At its top the blank terminates in a wide panel portion 11 carrying side ears 12 that are formed as shown in Figure 1. This panel 11 is oblique to the top horizontal part 8 to receive a legend 70 such as that shown in Figure 5, describing the article displayed.

Projecting outwardly from the bottom vertical crease lines 13 and 14 are side wing portions 15. Above an inclined crease line 16 75 each side wing portion is formed with a flap 17 from whose inner end the lower ear of the middle portion of the blank has been severed. A V notch 18 is between the outer end of each flap 17 and the upper outer corner of its side 80 wing 15.

Within each wing portion 15 there is a series of inclined slots 19 that may project a slight distance into the flap part 17. In folding the blank the flaps 17 are bent inwardly 85 while the side wings 15 to which they are attached are turned to positions at right angles to that part of the blank which is below the crease line 2. (See Figure 4). The middle portion of the blank is then folded to bring 90 its parts 8 to horizontal positions and its parts 10 to vertical positions, after which the ears 5 and 6 are tucked in the slots 19 that are reinforced by the side flaps 17. The side wings 15 contain in their upper, outer corner portions slots 20 to receive the ears 12 on the panel parts 11 of the blank. With its parts thus firmly connected together, the folded

blank is shown in Figure 4 as a terraced display-support for some of the articles of merchandise contained in the box 21 illustrated in Figure 5. Adapted to be contained in its 5 dissembled state in this box, it is inserted therein in its set-up position over the articles of merchandise which it contains, to support upon its horizontal terraced portions 8 some of said articles without interfering with the 10 removal of the remaining ones from the rear end of the box.

In Figure 6 I have shown one side of a blank 1 whose side wing portions 15 are formed with different top flaps than those 15 shown in Figure 1. Each top flap, which is designated by the numeral 23, is divided from its side wing by V slots 24. Accordingly, when the flap 23 is bent against the inner surface of its side wing 15, as shown in Figure 9, 20 the tongue portions 25 left when the slots 24 are formed will project horizontally to provide side supports for the horizontal terraced parts 8 whose ears 5 and 6 are received by the V slots 24.

25 In many different ways these side wing flaps and slots may be formed to firmly receive the ears on the terraced portion of the blank without departing from the scope of the invention, the essence of which is to provide a firm, attractive and economically made terraced display-support for articles of merchandise in a paper box without interfering with the removal of the remaining articles therefrom. The top flaps which the wings 30 carry reinforce the slots in the latter, said slots being engaged at their upper and lower ends by the ears on the terraced part of the blank.

I do not wish to be limited to the details of 40 construction and arrangement herein shown and described, and any changes or modifications may be made therein within the scope of the subjoined claims.

Having described my invention, I claim:

45 1. A terraced display-support comprising a blank with a middle part having transverse crease lines by which said section may be folded into terraced form, side wings at the lower ends of said middle section of the blank and having upwardly inclined top edge portions, and projections on the middle portion of the blank for securing the side wings thereto when the latter are folded inwardly against said middle part after it is 50 creased to terraced form.

2. A terraced display-support for insertion in a paper box, comprising a blank with a middle part having transverse crease lines by which said section may be folded into terraced form, side wings at the lower ends of said middle part of the blank and having upwardly inclined top edge portions formed 55 with slots, and ears formed on the middle part of the blank for entrance into the slots in said side wings when the latter are folded

inwardly against said middle part after it is creased to terraced form.

3. A terraced display-support comprising a blank with a middle part having transverse crease lines by which said part may be 70 folded into terraced form, side wings at the lower ends of said middle part of the blank and having inwardly foldable, upwardly inclined top flaps, said side wings containing slots in their upper portions, and ears formed 75 on the middle part of the blank for entrance into the slots in the side wings when the latter, with the top flaps bent over, are folded inwardly against said middle part after it is creased to terraced form.

80 4. A terraced display-support comprising a blank with a middle part having transverse crease lines by which said part may be folded into terraced form, side wings at the lower ends of said middle part of the blank 85 and having upwardly inclined top edge portions, projections on the middle portion of the blank for securing said side wings thereto when the latter are folded inwardly against said middle part of it, said terraced 90 portion of the blank having an end part to display legends, and means for securing said end part in an upwardly inclined position, to said side wings.

95 5. A terraced display-support for insertion in a paper box, comprising a blank with a middle part having transverse crease lines by which said section may be folded into terraced form, those portions of the blank between the crease lines which provide the 100 horizontal supporting surfaces terminating at their ends in ears, and side wings at the lower ends of the middle section of the blank and having upwardly inclined top edge portions formed with slots to receive 105 the ears on the terraced portion of the blank for the purpose specified.

110 6. A terraced display-support comprising a blank with a middle part having transverse crease lines by which said section may be folded into terraced form, those portions of the blank which provide the horizontal 115 supporting ledges, terminating at their ends in ears, side wings at the lower ends of the middle part of the blank, and supporting means for said horizontal ledges, formed at the top edges of said wings, said wings formed with staggered slots in their upper portions to receive said ears for the purpose specified.

120 7. A terraced display support comprising a blank with a middle part having transverse crease lines by which said part may be folded into terraced form, side wings at the lower ends of the blank and carrying top 125 flaps, said wings being formed with slots in their upper portions, and projections on the terraced part of the blank for entrance into said slots when said wings are folded toward said terraced part.

8. A terraced display-support comprising a blank with a middle part having transverse crease lines by which said part may be folded into terraced form, side wings at the lower ends of the blank and carrying top flaps, said wings being formed with slots in their upper portions, and projections on the terraced part of the blank to engage the 10 slots at their upper and lower ends for the purpose specified.
- 5 In testimony whereof I have hereunto set my hand this 26th day of August, 1927.

THEODORE L. NEUMANN.
